UNITED STATES PATENT OFFICE.

JOHN E. O. PRIDMORE, OF CHICAGO, AND EARL C. MCKINNIE, OF OAK PARK, ILLINOIS,
ASSIGNORS TO CURTIS LIGHTING, INCORPORATED, OF CHICAGO, ILLINOIS, A COR-
PORATION OF ILLINOIS.

LIGHTING FIXTURE.

Application filed May 6, 1922. Serial No. 558,887.

To all whom it may concern:

Be it known that we, JOHN E. O. PRIDMORE and EARL C. MCKINNIE, citizens of the United States, residing, respectively, at Chicago and Oak Park, in the county of Cook and State of Illinois, have invented certain new and useful Improvements in Lighting Fixtures, of which the following is a specification.

10 The present invention is related to the art of illumination, and more particularly to the fixtures thereof.

Crystal chandeliers have been employed hitherto for the general illumination of auditoriums as well as the smaller apartments of residences and other buildings. The pronounced beauty and magnificence of these fixtures have outweighed the disadvantages of the harmful and irritating glare resulting therefrom as these fixtures are usually constructed. Little, if any, effort has been made towards overcoming the objectionable characteristics referred to, so that the crystal fixture stands today with its inherent 25 disadvantages in the diffusion of the light emanating therefrom.

The present invention, therefore, has as its primary object the provision of a fixture of the class referred to wherein its artistic 30 value is retained, but which possesses the added qualities of being light-giving and glareless. The invention imparts to the fixture capacity for indirect illumination, thereby enabling the light which emanates 35 therefrom to be reflected or distributed in a highly diffused manner throughout the space in which the fixture is located.

A further object of the invention is to provide a lighting fixture having for its 40 illumination units arranged both internally and externally thereof, thus obtaining the advantages of refracted light from the internal units, and of reflected light developed from the external units, whether the light 45 from these sources be utilized individually or collectively.

The invention also seeks to provide an improved lighting fixture wherein is incorporated a plurality of illuminating units so 50 arranged and correlated as to provide for a multiplicity of color effects susceptible to a wide range of variation. The artistic value of the crystal chandelier thereby is enhanced by the changing color combinations, the struc-

ture possessing the added value of freedom 55 from glare and irritation of the eyes of the observer.

Other objects and advantages will appear as the nature of the improvements is better understood, the invention consisting substantially in the novel construction, combination and arrangement of parts hereinafter fully described, illustrated in the accompanying drawings, and finally pointed out in the appended claims.

A particular embodiment of the invention is disclosed herein for presenting the inventive concept, but by reason of the susceptibility of the same to modification and variation in order to meet particular needs, the 70 form shown is to be considered only from the illustrative standpoint, and not as imposing restriction or limitation on the invention.

In the drawings,

Fig. 1 is a vertical sectional view, partly 75 in elevation, of a lighting fixture constructed in accordance with the present invention;

Fig. 2 is a sectional plan view on the line 2—2, Fig. 1;

Fig. 3 is a side elevation, on an enlarged 80 scale, of the major supporting bracket employed with the fixture;

Fig. 4 is a sectional plan view thereof;

Fig. 5 is a perspective view of one of the light boxes with its cover illustrated in dis- 85 associated relation thereto.

The illuminating units of the herein-described fixture are constituted by electric lamps of varying wattage as determined by the particular point where they are applied 90 in the fixture structure, and the function which each is to perform in the quota of light which the same is designed to contribute to the general illumination of the fixture. These lamps form no part of the 95 present invention, nor does the wiring of the fixture as required for the illumination of the lamps. Any character of lamps may be employed, and any suitable system of wiring may be utilized in connection with the fixture. 100

The numeral 10 designates a tubular supporting standard, such as a pipe of the required diameter, the wiring for the fixture being received by this standard from the circuit leads which supply the lamps with the necessary current. There is included, of course, in the wiring suitable switches for 105

controlling the several lamps, and for providing the various combinations thereof when producing the varied colored effects. Such switches are no part of the present invention, and reference thereto need not further be made.

At the lower end of the standard 10 is arranged a major supporting bracket 11, which bracket includes a centrally disposed tubular stem 12 at the exterior of which is arranged radial webs 13, and at the upper end of which is located a wiring junction box 14. The bracket 11 is suitably connected to the standard 10, and said bracket has attached thereto a plurality of radially extending horizontally disposed supporting arms 15, formed preferably of angle-iron. At the outer ends of the arms 15, and suitably connected thereto, is a major sustaining ring 16. This ring marks the greatest diameter of the bowl portion of the fixture, and certain of the crystals, as hereinafter described, are suspended therefrom.

Suitably connected to the top portion of the standard 10 is an upper sustaining ring 17, and suspended from said ring 17 are the upper ends of a plurality of strands of crystals 18, the lower ends of said strands being connected to the major sustaining band 16. The strands 18 collectively constitute the column of the fixture, and the diameter of the ring 17 is such that a relatively large space is provided at the interior of the strands 18. This space is utilized for illumination purposes.

At the lower end of the fixture is a lower sustaining ring 19, the diameter of this ring being relatively small, and to said ring 19 are connected the lower ends of a plurality of strands of crystals 20 the upper ends of which are connected to the major sustaining ring 16. The strands 20 constitute the bowl of the fixture, and the space within said strands 20 or bowl portion is also utilized for illuminating purposes.

Both the major sustaining ring 16 and the upper sustaining ring 17 are employed for supporting annular series of lamps 21 and 22, respectively, but these lamps are of relatively low wattage. They afford direct illumination, but because of their low wattage the illumination afforded thereby is not offensive to the eye, nor do these lamps cause irritation.

For adding to the further decorative effect of the fixture the rings 16 and 17 also support annular series of crystal leaves 23 and 24, respectively, and from said leaves there are dependent series of crystal pendants 25 and 26, respectively. At the lower end of the fixture, and sustained by the ring 19 thereat, are further pendant crystals 27, in order to impart symmetrical ornamentation at this point.

It has been stated that one of the objects

of the present invention is to provide a lighting fixture the illuminating units of which are arranged both internally and externally thereof, thereby to obtain the advantages of refracted light from the internal units, and of reflected light from the external units. To this end a depending tubular extension 28 is connected to the lower end of the major bracket 11, this extension being in communication with the stem 12 thereof, and said extension 28 is provided with a plurality of spaced junction boxes 29. Tubular arms 30 are connected to the several junction boxes 29, which arms are arranged in radial relation to said junction boxes, and each terminates in a lamp socket 31 of suitable structure for the application of electric lamps 32. The length of the arms 30 of the several series varies in order to project the lamps 32 of each series in sufficient proximity to the crystal strands 20 for obtaining the greatest illumination of the same. The lamps 32 supply the requisite light for illumination of the bowl of the fixture.

Distributed throughout the length of the standard 10, and spaced at the desired intervals therealong, is a plurality of junction boxes 33 from which extend radial tubular arms 34 terminating in sockets 35 to which lamps 36 are applied. These lamps provide the necessary illumination for the column of the fixture. To carry out the desired color scheme the bulbs of the lamps 36, as well as of the lamps 32 in the bowl of the fixture, are colored in the shades necessary for the scheme. The combination of these colors, and the combination of the lamps for the several colors, is determined by the particular effect which it is desired to produce, and the several lamps are controlled by the switches hereinbefore referred to as embodied in the wiring system in order to produce the colored effects for which the lamps are designed.

Obviously, with the lamps 32 and 36 concealed at the interior of the fixture, the rays of light emanating therefrom are refracted by the crystal strands 18 and 20, so that not only are the colors of the lamps utilized for the illumination of the crystals, but the refraction of the rays emanating from these lamps also contributes to the effect produced from the illumination within. Due to the fact that the lamps 32 and 36 are concealed, there is no direct illumination at the exterior of the fixture from these lamps.

The indirect illumination is obtained by a plurality of light boxes 37 arranged in a plurality of groups located in different horizontal planes. As illustrated, two of these groups are employed. The boxes 37 of each group are respectively supported by tubular arms 38, the inner ends of said arms being connected to the junction box 14, and the outer ends supporting sockets

39 with which lamps 40 are associated. The arms 38 of the upper group are shorter than the arms of the lower group, so that the boxes 37 of the lower group are arranged nearer of the fixture.

5 to the peripheral edges of the bowl than are the boxes of the upper group. Furthermore, it is apparent that the herein-described invention more, the boxes of the two groups are arranged in staggered relation with respect to each other; so that they occupy the spaces between the boxes of the other group.

Each of the boxes 37 comprises a substantially rectangular housing 41, closed as to all of its portions with the exception of its top, and around the top, and adjacent to its edge portion, is a supporting ledge 42 on which is removably located a screen 43 formed of colored glass. The color of the glass, therefore, controls the color of the light emanating from each of the boxes, and this light is projected against the exterior of the crystal strands 18 of the column of the fixture as well as against the ceiling or canopy from which the fixture is suspended. To provide for this a suitable high-powered reflector 44, preferably of the hooded type with a silver mirrored back, is arranged within each of the light boxes 41, and surrounds the lamp 40 in said box. The rays projected by these reflectors 44 through the various colored screens 43 impinge against the crystal strands 18 and the ceiling or canopy over the fixture, being reflected or distributed thereby in a highly diffused manner throughout the auditorium or room in which the fixture is located.

35 By reason of the varying colors of the screens 44, the lamps of the boxes 37 create translucent glass commonly found in fixtures of this general character. They become luminous, therefore, when the lamps illuminate the auditorium or other locality where the fixture is placed with a diffused light. These crystals, however, may be formed of varying colors in accordance with the other material suitable for the purpose and particular lamps which are rendered luminous by the switching connections in the several circuits.

45 That the boxes may be protected against the heat generated by the lamps therein, the side walls of each box are provided with ventilating openings 45 to permit air circulation within the box and escape of the heat therefrom.

The upper end of the fixture is surmounted by a plurality of light boxes 46, similar in all respects to the light boxes 37, said boxes 46 being supported by radial arms 47 connected to a junction box 48 carried by the standard 10. The light reflected by the boxes 46 from the lamps contained therein is projected upwardly against the surface, whether it be the ceiling or canopy, over the fixture. This upper series of boxes thereby provides a zone of light which is separate and distinct from the zones created by the boxes 37, and the color effect of this upper zone may correspond with or be varied from

the colored zones created by the boxes 37, the latter being worked out by the operation of the color instrumentalities.

From the foregoing description it will be apparent that the herein-described invention affords a lighting fixture through the medium of which a most extended scheme of color illumination may be had in addition to the pronounced and artistic effect flowing

from the utilization of a crystal fixture considered apart from the schematic arrangement of the color instrumentalities. The lamps enclosed within the fixture give a radiance to the latter changeable in accordance with the switching connections of the wiring system, regardless of whether or not the light from the lamps on the exterior of the fixture is employed, while the utilization of these exterior lamps extends the illumination in accordance with the particular effects designed to be produced by such exteriorly disposed lamps, and whether both are used simultaneously or independently of each other, and whether or not the lamps at one portion of the fixture are caused to become luminous to the exclusion of the others.

The invention lends itself to the development of varying combinations of color effects the limit of which is controlled only by the colors employed and the switching connections of the wiring system for effecting the varying combinations of the colors in the room in which the fixture is located. The crystals employed in the herein-described fixture preferably are formed of the translucent glass commonly found in fixtures of this general character. They become luminous, therefore, when the lamps illuminate the auditorium or other locality where the fixture is placed with a diffused light. These crystals, however, may be formed of varying colors in accordance with the other material suitable for the purpose and particular lamps which are rendered luminous by the switching connections in the several circuits.

45 We claim:

1. A lighting fixture of the class described, comprising a translucent body, means within the body for illuminating the latter by refracted light, means at the exterior of said body for illuminating the latter by reflected light, and a source of light associated with the body at a point remote from said internal and external illuminating means for maintaining by indirect illumination a light zone in proximity to the body.

2. A lighting fixture of the class described, comprising an elongated translucent body, means within the body for illuminating the latter by refracted light, means adjacent to the basal portion of the body and at the exterior thereof for projecting light upwardly against the superjacent portion of the body for illuminating the latter by reflected light, and a source of light associated with the body at a point remote from

1. said internal and external illuminating means for maintaining by indirect illumination a light zone in proximity to the body.
2. A lighting fixture of the class described, comprising an elongated translucent body, means within the body for illuminating the latter by refracted light, means adjacent to the basal portion of the body and at the exterior thereof for projecting light upwardly against the superjacent portion of the body for illuminating the latter by reflected light, and means at the top of the body for maintaining a light zone thereat by indirect illumination.
3. A lighting fixture of the class described, comprising a translucent body including a bowl portion and a column portion thereabove, the column portion being of less diameter than the bowl portion, means within the bowl and column portions for illuminating the same by refracted light, and means above the bowl portion and exterior to the body for illuminating the column portion by reflected light.
4. A lighting fixture of the class described, comprising a translucent body including a bowl portion and a column portion thereabove, the column portion being of less diameter than the bowl portion, means within the bowl and column portions for illuminating the same by refracted light, means above the bowl portion and exterior to the body for illuminating the column portion by reflected light, and means at the top of the column portion for maintaining a light zone thereat by indirect illumination.
5. A lighting fixture of the class described, comprising a translucent body including a bowl portion and a column portion thereabove, the column portion being of less diameter than the bowl portion, means within the bowl and column portions for illuminating the same by refracted light, means above the bowl portion and exterior to the body for illuminating the column portion by reflected light, and means at the top of the column portion for maintaining a light zone thereat by indirect illumination.
6. A lighting fixture of the class described, comprising a body formed of crystals and including a bowl portion and a column portion thereabove, the column portion being of less diameter than the bowl portion, means within the bowl and column portions for illuminating the same by refracted light, and means above the bowl portion and exterior to the body for illuminating the column portion by reflected light.
7. A lighting fixture of the class described, comprising a body capable of being rendered luminous, lighting units at the interior of said body for illuminating the same from within, lighting units at the exterior of said body for illuminating the same from without, and means included in both the interior and exterior lighting units for effecting illumination of the body in varying colors.
8. A lighting fixture of the class described, comprising a body capable of being rendered luminous and including a bowl portion and a column portion thereabove, the column portion being of less diameter than the bowl portion, lighting units at the interior of the bowl and column portions for illuminating the same from within, lighting units at the exterior of said body for illuminating the same from without, and means included in both the interior and exterior lighting units for effecting illumination of the body in varying colors.
9. A lighting fixture of the class described, comprising a body formed of crystals and including a bowl portion and a column portion thereabove, the column portion being of less diameter than the bowl portion, lighting units at the interior of the bowl and column portions for illuminating the same from within, lighting units at the exterior of said body for illuminating the same from without, and means included in both the internal and external lighting units for effecting illumination of the body in varying colors.
10. A lighting fixture of the class described, comprising a body capable of being rendered luminous, lighting units at the interior of said body for illuminating the same from within, and a plurality of light boxes at the exterior of said body for illuminating the same from without, each of said light boxes including a lighting element and a reflector adapted to project the light from said element against the exterior of said body.
11. A lighting fixture of the class described, comprising a body capable of being rendered luminous, lighting units at the interior of said body for illuminating the same from within, a plurality of light boxes at the exterior of said body for illuminating the same from without, each of said light boxes including a lighting element, a reflector adapted to project the light from said element against the exterior of said body, and a color screen associated with the box to intercept and color the rays projected therefrom.
12. A lighting fixture of the class described, comprising a body formed of crystals and including a bowl portion and a column portion thereabove, the column portion being of less diameter than the bowl portion, lighting units at the interior of said bowl and column portions for illuminating the same from within, a plurality of light boxes at the exterior of said body for illuminating the same from without, each of said light boxes including a lighting element, a reflector adapted to project the light from said element against the exterior of said body, and a color screen associated with the box to intercept and color the rays projected therefrom.
13. A lighting fixture of the class described, comprising a body formed of crystals and including a bowl portion and a column portion thereabove, the column portion being of less diameter than the bowl portion, lighting units at the interior of said bowl and column portions for illuminating the same from within, a plurality of light

boxes adjacent to the basal portion of the body and at the exterior thereof for projecting light upwardly against the exterior of the column portion, a plurality of light boxes arranged within the column portion adjacent to its top for maintaining a light zone thereat, each of said light boxes including a lighting element, a reflector adapted to project the light from said element against the exterior of said body, and a color screen associated with the box to intercept and color the rays projected therefrom.

14. A lighting fixture of the class described, comprising a body formed of crystals, means within said body for rendering the latter luminous, and indirect lighting units arranged at the exterior of the body for effecting indirect illumination thereof, the rays emanating from said indirect lighting units being diffused by the body. 15 20

In testimony whereof we have hereunto subscribed our names.

JOHN E. O. PRIDMORE.
